UNITED STATES PATENT OFFICE.

JULIUS B. SAPP, OF CLEVELAND, OHIO.

OBTUNDER.

1,027,216.

Specification of Letters Patent.

Patented May 21, 1912.

Application filed July 10, 1911. Serial No. 637,843.

To all whom it may concern:

Be it known that I, JULIUS B. SAPP, citizen of the United States, residing at Cleveland, in the county of Cuyahoga and State of Ohio, have invented certain new and useful Improvements in Obtunders, of which the following is a specification.

This invention relates to obtunders, and has for its object to provide an improved device of the kind, characterized especially by new and improved means for manipulating the same, for adjusting the parts to vary the action of the instrument, and for controlling the movements of the various parts, as will more fully appear from the following description and the drawings.

In the accompanying drawings—Figure 1 is an elevation of the left side of the instrument. Fig. 2 is a longitudinal section. Fig. 20 3 is a partial elevation of the right side of the instrument. Fig. 4 is a section on the line 4—4 of Fig. 1.

Referring specifically to the drawings, 6 indicates a barrel provided at the front end with the usual removable point, and 8 is a plunger the front end of which works in said barrel. The barrel is enlarged at its rear end to form a chamber for the packing ring 16 and the leather washers 23. The 25 barrel screws at its rear end into a stock 10, and may have a knurled ring or part 7 for ornament if desired. The stock has a rearwardly extending part or neck 18 integral therewith, also a depending or down- 30 wardly extending part or sleeve 40 in which slides a rod 11, and below the sleeve or stock is a recessed boss 41 in which an adjusting nut 13 turns, said nut being mounted on the front end of a finger piece 15 which 35 slides through the hole in the lower end of a guide piece 14 which is clamped to the rod 11 by a screw 21, the piece 14 being split vertically on its middle line to enable it to be clamped to the rod by the screw 21. 40 Above the rod 11 the handle 12 has a forwardly extending tubular socket 20, parallel to said rod, which socket receives the rear end of the plunger 8, the plunger having a key way 25, and the socket a key 24 fitting therein, to prevent the plunger turning. The plunger is threaded for a part 45 of its length, near the rear end thereof, and on the threaded part is a thumb nut 9, which is located between the end of the 50 socket 20 and the upper part of the piece 14, and by turning the thumb nut the plun-

ger may be advanced or retracted for purposes hereinafter stated. Ball bearings 17 are provided between the end of the socket and the nut for ease of turning. 60

As shown especially in Fig. 4, the stock 10 has mounted therein a latch which is engageable with a rack 10^a in the side of the rod 11. This latch consists of a small rod 19 which works transversely through a bore 65 19 in the stock, and at the right end the rod has a head 19^a to receive thumb pressure, and at the left end has a depending part 19^b which works in a recess in the side of the stock, and on its inner face has a tooth 19^c 70 which engages in one of the notches in the rack 10^a. A spring 19^d under the head 19^a, normally holds the latch in engagement with the rack. 75

The operation is as follows: To fill the instrument, the amount of liquid is first regulated approximately by adjusting the plunger by means of the nut 9, which advances or retracts the same to decrease or increase the capacity of the barrel. Then 80 the thumb piece 19^e is pressed to release the latch, and, the point of the instrument being placed in the obtunding liquid, the handle and the parts fixed thereto, including the piece 14, are pulled back with respect to the 85 barrel, thereby drawing a quantity of liquid into the barrel. The pressure on the thumb piece 19^e is then released, permitting the latch to engage the rack and lock the parts against relative movement. Then the point 90 of the instrument is placed or pressed in the tooth, being guided and pressed into position conveniently by the index finger, for which a print or depression 22 is made in the right hand side of the stock 10, to 95 receive the tip of the finger. When the instrument is in proper position, the latch is released by pressure on the head 19^a, and then, while the instrument is held in place, the plunger is advanced by the pressure of 100 the hand and the finger engaging the finger piece 15, drawing the handle and said finger piece toward each other. After this, additional pressure may be exerted if necessary, by turning the nut 9 in the proper direction. By means of the nut 13 which screws 105 on the finger piece 15 the distance of said finger piece from the handle may be adjusted, to suit hands of different sizes.

I am aware that syringes of this type 110 have been proposed in which the pressure is made and maintained by compression of

the hand, but in the use of the device continuous compression must be maintained for several minutes, which in such devices causes the hand to become numb and the fingers cramped, in which condition the hand is unable to perform the delicate operations required; also, ordinary hand pressure is insufficient. With my instrument the preliminary pressure is made by compression of the hand, and an additional or high pressure is made by turning the thumb wheel, forcing the piston forward, and automatically maintaining the high pressure, which is very essential, without any additional effort on the part of the operator, leaving the hands and fingers in a natural condition, without having been strained or cramped.

What I claim as new is:—

1. An instrument comprising a stock, a barrel fixed thereto, a handle having a projecting guide rod on which the stock is slideable, a latch between the stock and rod, to lock the parts against movement, and a plunger connected to the handle and working in the barrel.

2. An instrument comprising a handle having a projecting guide, a plunger connected to the handle, a barrel slideable on the guide and in which the plunger works, and means to lock the handle and barrel against relative movement.

3. An instrument comprising a stock, a barrel projecting therefrom, a finger piece connected to the stock, a handle having a guide on which the stock is slideable, and a plunger connected to the handle and working in the barrel, the handle and finger piece being arranged in position to be grasped for manipulation.

4. An instrument comprising a handle having a projecting guide rod and a socket, a stock slideable on the rod, a barrel fixed to the stock, in line with the socket, a plunger the rear end of which fits in the socket and the front end of which works in the barrel, and means mounted on the socket to adjust the plunger in or out.

5. An instrument comprising a handle having a projecting guide rod and a socket, a stock slideable on the rod, a barrel fixed to the stock, in line with the socket, a plunger

the rear end of which fits in the socket and the front end of which works in the barrel, and a nut mounted on the plunger at the end of the socket, to advance or retract the former, the plunger being threaded for a part of its length, to receive the nut.

6. An instrument comprising a handle having a projecting tubular socket, a plunger the rear end of which is slideable lengthwise in the socket, means to prevent rotation of the plunger, a nut mounted on a threaded part of the plunger at the front end of the socket, and a barrel in which the front end of the plunger works.

7. An instrument comprising a handle having a projecting guide rod with a rack thereon, a plunger attached to the handle, a stock slideable on the rod, a latch carried by the socket and engageable with the rack to latch the stock to the rod, and a barrel fixed to the stock and in which the plunger works.

8. An instrument comprising a barrel, a handle slidably connected to the barrel, a plunger working in the barrel and attached to the handle, whereby it may be advanced or retracted by relative movement of the handle and barrel, and means to advance or retract the plunger independent of the relative movement of the barrel and handle.

9. An instrument comprising a barrel, a plunger working therein, a handle operatively connected to the plunger, to advance the same for initial pressure in the barrel, and means to advance the plunger independently of the handle, for additional pressure in the barrel.

10. An instrument comprising a barrel, a plunger working therein, a handle operatively connected to the plunger to advance the same for pressure in the barrel, means to secure the handle and barrel against relative movement, and means to advance the plunger with respect to the handle, farther into the barrel, for additional pressure therein.

In testimony whereof, I do affix my signature in presence of two witnesses.

JULIUS B. SAPP.
